UNITED STATES PATENT OFFICE.

CALVIN N. SOUTHER, OF CHICAGO, ILLINOIS, ASSIGNOR TO POOLE BROTHERS, OF SAME PLACE.

TICKET-STAMP.

SPECIFICATION forming part of Letters Patent No. 529,669, dated November 20, 1894.

Application filed September 22, 1893. Serial No. 486,182. (No model.)

To all whom it may concern:

Be it known that I, CALVIN N. SOUTHER, a citizen of the United States, residing at Chicago, in the county of Cook and State of Illinois, have invented certain new and useful Improvements in Ticket-Stamp; and I do hereby declare the following to be a full, clear, and exact description of the invention, such as will enable others skilled in the art

10 to which it appertains to make and use the same, reference being had to the accompanying drawings, and to letters of reference marked thereon, which form a part of this specification.

15 This invention relates to improvements in ticket stamps of that class which are adapted to simultaneously stamp the ticket and sever therefrom an auditor's stub or check, which is preserved as a record of the sale.

20 The object of the invention is to provide an improved construction in ticket stamps of the character referred to; and it consists in the matters hereinafter set forth and particularly pointed out in the appended claims.

25 In the accompanying drawings: Figure 1 is a front elevation of a stamp constructed in accordance with my invention, the upper portion being in elevation and the lower portion in section of Fig. 3. Fig. 2 is a rear elevation. Fig. 3 is a longitudinal section of Fig. 1. Fig. 4 is a vertical, transverse section of Fig. 3. Fig. 5 shows the style of ticket adapted to be severed thereby.

30 A designates the base of the stamp in the top of which is formed an opening A'.

35 B designates a type-plate supported horizontally in the opening A' upon a bridge B' extending across the said opening A'. This type-plate may have upon its upper face any letters or figures that it may be desirable to print upon the ticket, and the plate may be made removable in order that other plates bearing different letters may be readily substituted. Said type-plate may be supplemented by disks C C' C'', bearing types upon their peripheries, and extending upward through the bridge B' and type-plate B. The disks C' is herein shown as rigidly secured upon a horizontal shaft D journaled in the

40 casing A', and the front end of which extends through the wall of the casing and terminates

in a milled head D², by means of which said shaft and disk may be rotated. Said shaft may also be provided without the casing with an indicated dial D³ for determining the position of the disks D. The disks C' and C'' are herein shown of annular form, and are rotatively mounted upon stationary bushings D' which loosely surround the shaft D, and are concentric therewith. The positions of the disks C C' are changed by turning them directly with the hand or by the use of a hand tool. Usually the name of a railroad or person using the stamp is placed upon the type-plate B, while the years, months and days are placed upon the disks C and C'.

E designates a ribbon shaft at the left of the type-plate, and E' a similar shaft at the right thereof, both shafts being horizontally journaled in the casing A'. The front end of the shaft E' extends through the front wall of the casing and terminates in a milled head E² by means of which it may be easily rotated. The rear end of the shaft E' extends through the rear wall of the casing and carries a rigidly attached wheel adapted to be intermittently actuated as the stamp is operated. An ordinary inking ribbon F is attached at its ends to the shafts E and E' and extends over the type-plate B in a well known manner. By rotating the shaft E, the entire ribbon, except that portion which must necessarily extend over the type-plate and the shaft E', may be wound upon the said shaft E, and as the stamp is operated, the ribbon will be gradually fed across the type-plate and wound upon the shaft E'. The inking mechanism thus described, as well as the type plate and disks, and also the shaft and dial have been previously used in similar relations, and in themselves constitute no part of my invention.

Rigidly secured to the base A is an upwardly extending arm or standard A², shaped at its upper end to form a forwardly curved neck 95 terminating in a vertical sleeve A³ within which a plunger G is adapted to reciprocate. Said plunger carries at its lower end a platen G² and terminates at its upper end in a head or hand piece G'. A spring g surrounding the plunger and acting on the head G' thereof serves to normally maintain the same in its

raised position. The distance between the type-plate B and the platen G², when the plunger is in its normally elevated position, is sufficiently great to permit the ready insertion of the tickets between said plate and the platen, as shown in Fig. 4. Upon the rear side of the platen G² a cutting blade H' is rigidly secured in any suitable manner, as by screws, and upon the rear of the casing A, 5 immediately at the rear of the type-plate B and substantially upon the same level thereof, is provided a cutting blade H, adapted to co-operate with the blade H' on the platen in severing the auditor's check from the ticket 10 as the latter is stamped. For the purpose of maintaining such constant relation between the blades H and H' as will insure a smooth and certain cutting action between them, the blade H' is provided at its ends with downwardly projecting arms h h extending behind 15 the blade H and long enough to constantly engage the same even when the platen is in its most elevated position.

The stub of the check detached by the action of the knives falls through a recess or 20 channel A⁵ provided in the casing of the stamp, at the base of the standard A² immediately behind the type-plate B and knife H, and opening downwardly into the interior of 25 the base A, said recess A⁵ being of sufficient width to readily admit any ticket which can pass between the arms h h. The rear side of said recess A⁵ is in this instance provided with a depending stop T⁸ adapted to limit the 30 distance to which the ticket is inserted between the knives. A door A⁶ at the rear of the case A enables the stubs cut from the ticket and deposited in the case A to be removed from the latter.

40 T, (Figs. 4 and 5) designates a card ticket provided with an auditor's stub T² designed to be severed from the body T' of the ticket along the line t, and to be preserved as a record of the sale. In the operation of the stamp 45 such tickets are thrust beneath the platen, with the stub passing between the arms h h, as shown in Fig. 4. The head G' of the plunger is thereupon struck by the hand, and the platen brought down upon the ticket, causing 50 the type plate and the dating wheels to print through the inking ribbon upon the under side of the ticket, while simultaneously therewith the stub is severed between the blades H' and H, and drops through the passage A⁵ 55 into the lower part of the case. On the other hand, long tickets, such as coupon tickets, may be readily stamped by passing them laterally beneath the platen, and in such cases, the depending portions h h of the blade H' serves 60 as a guard to prevent the edge of the ticket from being mutilated by the blades, as the platen is depressed to make the impression. The attachment of the movable blade to the cutting mechanism, particularly in connection 65 with the means herein disclosed for insuring a uniform relation between the blades, is especially advantageous in structures of

this character, since it practically eliminates the possibility of the cutting mechanism becoming ineffective for lack of proper adjustment, and at the same time provides a cutting action of the type recognized as the most effective for severing thin sheets of flexible material (viz: a shearing cut between two blades the adjacent faces of which are maintained at all times in close contact) without the employment of any pivots or other working joints, which latter are liable to become worn and thereby permit the blades to spring apart in a manner to prevent their effective action. 70 The cutting mechanism, moreover, although automatically brought into operation whenever the stamp is used, and therefore always ready for effective action, is provided in such form as not to interfere in any way with the 75 separate use of the printing mechanism or the stamp proper.

In order to effect the intermitting rotation of the ratchet wheel E², hereinbefore referred to, an arm I extends laterally from the platen G² to a point beyond the side of the case A, near said ratchet wheel. A lever I² is journaled on the shaft E' at the side of the ratchet wheel E⁴. Said lever is provided with an upwardly extending arm I³ to the upper end of 95 which is pivoted a gravity-pawl I⁴, which engages the teeth of the wheel E². From the arm I depends an arm I' which engages one end of the lever I². At the opposite end of 100 said lever I² a contractile coiled spring I⁵ is attached; the opposite end of said spring being secured to a post of the case A below the lever. By this construction the ratchet wheel is actuated and the ribbon moved across the face of 105 the type in a step by step movement as the stamp is operated, and constantly presents a fresh inking surface to the work.

A printing mechanism having a type-plate over which a ribbon passes is herein shown merely for the purpose of illustration, it being understood that any other form of type-plate or die, either with or without dating disks or movable dating types, may be employed, and that any desired form of inking mechanism for the types of the stamp may be 110 used, or that cutting or embossing types or dies, without any inking device, may be used in carrying out my intention.

One important feature of my invention is embraced in the construction by which the standard which supports the sliding plunger is located at one side of the type support and the platen, and in which the stationary cutting blade and the movable cutting blade which is attached to the platen are located at 115 the side of the type support and the platen adjacent to said standard, so that the stamp may be used equally well for dating long or coupon tickets, or for simultaneously dating 120 and cutting the stub from small or card tickets, as hereinbefore set forth.

Another important feature of the invention is embraced in the construction in which the casing of the stamp at the side thereof adja-

cent to the said standard is provided with a recess which extends above the stationary cutting blade and is provided with an opening adjacent to the type support so as to receive the end of the ticket from which the stub is to be cut, this construction affording a suitable inclosure to receive the stub, which being located at one side only of the type support enables the stamp to be used either for 10 coupon or card tickets, as hereinbefore stated. It will of course be seen that the depending arms on the movable cutting blade not only serve to maintain the proper relation between the two cutting blades to insure the perfect 15 action thereof, but also serve as guards to prevent the side of a long or coupon ticket which is being operated upon from entering between and being mutilated by the cutting blades.

20 I claim as my invention—

1. A ticket stamp, comprising a type support, a vertically movable plunger, a platen attached to the lower end of the plunger and normally separated from the type support by 25 a free uninclosed space, a stationary horizontal cutting blade adjacent to the type support, a movable cutting blade rigidly attached to the platen and adapted to co-operate with the stationary blade in the descent of the 30 plunger, and a receptacle for stubs provided with an inlet opening, adjacent to the stationary cutting blade, through which the cut off stubs may enter the receptacle, substantially as described.

35 2. A ticket stamp, comprising a type support, a vertically movable plunger, a platen attached to the lower end of the plunger and normally separated from the type support by 40 a free uninclosed space, a standard for supporting the plunger located at one side of the type support and platen, a stationary blade having a horizontal cutting edge secured to the type support in approximately the same plane therewith, a movable cutting blade rigidly attached to the platen and provided at its ends with depending arms which are 45 constantly engaged with the stationary cutting blade, a recess in the supporting standard extending above and immediately adjacent to the cutting blade and open at the side adjacent to the type support to receive the end of the ticket, and a receptacle for detached stubs in communication with said recess, substantially as described.

stationary blade in the descent of the plunger, and a receptacle for detached stubs, said standard being provided with a recess in its side face opposite the stationary cutting blade, which recess is in communication with the 50 said receptacle, substantially as described.

3. A ticket stamp, comprising a type support, a vertically movable plunger, a platen attached to the lower end of the plunger and normally separated from the type support by 55 a free, uninclosed space, a stationary blade having a horizontal cutting edge and secured to the type support, and a movable cutting blade rigidly attached to the platen and provided at its ends with depending arms which are 60 constantly engaged with the stationary cutting blade, substantially as described.

4. A ticket stamp, comprising a type support, a vertically movable plunger, a platen attached to the lower end of the plunger and 65 normally separated from the type support by a free, uninclosed space, a standard for supporting the plunger located at one side of the type support and platen, a stationary blade having a horizontal cutting edge secured to 70 the type support in approximately the same plane therewith, a movable cutting blade rigidly attached to the platen and provided at its ends with depending arms which are 75 constantly engaged with the stationary cutting blade, a recess in the supporting standard extending above and immediately adjacent to the cutting blade and open at the side adjacent to the type support to receive the end of the ticket, and a receptacle for detached stubs 80 in communication with said recess, substantially as described.

In testimony whereof I affix my signature, in presence of two witnesses, this 16th day of September, 1893.

CALVIN N. SOUTHER.
